SEPARABLE FASTENER

Richard A. Hatch, New Rochelle, N. Y., assignor
to Talon, Inc., a corporation of Pennsylvania

Application October 4, 1937, Serial No. 167,091

5 Claims. (Cl. 24—205.5)

My invention relates to separable slide fasteners and particularly to lock sliders, an example of which is described and claimed in the Norton et al. Patent No. 1,966,457, issued July 17, 1934.

The slider of the above-mentioned patent has been in large production for a considerable period of time and is satisfactory for many purposes. On some types of garments, however, for example a corset, the slider will sometimes be pulled almost to the end of its movement but not all the way to the end. The automatic lock will function then to lock the slider in place and when the attempt is made to pull the garment off, great force will be applied to the sides of the opening. This will put a very severe strain on the locking device and on the bottom parts of the fastener and goods to which the fastener is attached, which may result in serious damage to one or more parts of the fastener assembly.

The principal object therefore of my invention is to provide an improved slider which, while retaining all of the normal functions and advantages of the Norton et al. patent, will overcome the difficulty referred to.

It will be observed that if an automatic lock slider is provided which will automatically go into locking position whenever the pull is released during the closing movement of the slider, but which will not lock if the pull is released during the opening movement of the slider, then the difficulty will be overcome and at the same time, automatic locking provided whenever needed. In general, therefore, my invention provides means on the locking parts which will function to hold the lock in its released position whenever the pull is released during the opening movement.

In the accompanying drawing, I have shown for purposes of illustration, two embodiments which my invention may assume in practice. In the drawing:

Fig. 1 is a plan view of a slide fastener equipped with my improved locking device;

Fig. 2 is a side view of the slider on a section of fastener with parts broken away to facilitate illustration;

Fig. 3 is a cross-section view on the line 3—3 of Fig. 1;

Fig. 4 is a perspective view of the upper slider body with parts broken away to facilitate illustration;

Fig. 5 is a longitudinal central section through the slider with the locking arm in unlocked position;

Fig. 6 is a view of the slider showing the unlocked position;

Fig. 7 is a view of the slider showing locked position;

Fig. 8 is a view of a slider of slightly varied form with the locking arm removed; and

Fig. 9 is a view similar to Fig. 7, but with the locking arm in place and showing the slider in unlocked position.

In carrying the invention into effect, the slider is formed of any suitable size and shape to fit the fastener on which it is used. The fastener illustrated is a well-known type comprising fabric tapes 8, having closely spaced interlocking fastener elements 9, attached to the adjacent edges of the tapes. The slider body 10 comprises upper and lower plates 11 and 12 respectively, with side flanges 13 for guiding the fastener elements into engagement. The upper and lower plates are connected by the integral neck 14.

A lug 15 is formed on the body of the slider, such lug being preferably elongated lengthwise of the slider and having at one end a hole or indentation 16 and at the other end a shoulder or projection 17. A locking arm 18 in the form of a hollow sheet metal member having top and side walls and preferably end walls, is mounted over the lug 15 and is pivotally attached to said lug adjacent one end by projections 19 extending into the indentation 16. The side walls of said arm 18 have inclined surfaces 20 and 21 and near the free end a recess or notch 22. The lug has a recess 23 in which is anchored a flat leaf spring 24. This spring extends over the lug to the other side of the pivot and bears against the internal surface of the back wall of the locking arm 18. At the opposite or free end the locking arm 18 has a pointed projection 25 formed as an extension of one side wall, which normally projects through the opening 26 in the top plate of the slider body into engagement with the fastener elements as seen in Fig. 2. The action of spring 24 on the locking arm is such as to tend to urge the locking projection into locking position between any pair of fastener elements, as seen in Fig. 2.

The pull tab 27 may be of any convenient form and the one shown herein is bifurcated at one end to embrace the locking arm. The ends of the bifurcations are turned inwardly to form pivot lugs 28. The pull tab when used for operating the slider to open the fastener engages the inclined surfaces 20, said surfaces directing slider pivot lugs 28 into recess or channel 22, said chan-

- nel or recess being of proper proportions in conjunction with slider pivot lugs 28 to lift locking projection 25 out of engagement with the fastener elements.
5. The recesses are designed and are of such size that the pivot lugs 28 will snap into them, and when the pull tab is released in that position, the pivot lugs will hold the locking member out of locking engagement.
10. In the modified form there is no alteration of the locking arm from the former construction, but instead there are one or more small bumps or projections 29, formed integral with the slider in the location illustrated so that when the pull tab is pulled to a forward position, the pivot lugs lock or snap behind these bumps and hold the locking arm in unlocked position. The same result will be accomplished as in the preferred form above described.
15. In operation when the fastener is being closed, the pull tab will move to the right of the slider, as viewed in the drawing, and the pivot lugs will engage the inclined surface 21. This will tend to lift the locking arm to unlocked position, and in any case the locking point is designed with an inclined surface to the rear so that it will never prevent movement of the slider to close the fastener. If, however, the pull tab is released at any position during such closing movement, the 20 spring will cause the locking arm to move automatically to locked position as more fully described in the Norton et al. patent above referred to. On the other hand, in opening the fastener, the slider will automatically unlock, but if the pull tab is now released, the slider will not automatically lock. The result is that when the wearer of the garment fails to move the slider deliberately all the way to the end of its travel in opening the fastener, a force placed on the slider will 25 move it to completely open position without any excessive stress being placed on the slider or adjacent parts. Accordingly, we believe that a large number of fastener failures will be eliminated, especially in such garments as corsets.
30. While I have shown and described in this application two embodiments which my invention may assume in practice, these embodiments are merely for the purpose of illustration and description, and various other forms may be devised 35 within the scope of my invention as set forth in the appended claims.
45. What I claim is:
1. In a slide fastener of the class described, a slider movable from one end to the other of the 40 fastener for opening and closing the same, a pull member connected to the slider, a slider locking device having means engageable by said pull member, means for automatically moving the locking device to locked position when the pull member is released at any position during the 45 closing movement of the slider, and means co-operating with said pull member for holding the locking device in unlocked position when the pull member is released during opening movement of the slider.
2. A slider for slide fasteners of the class described comprising a slider body, a locking member connected thereto and movable relative to the slider body to locked and unlocked positions, a pull tab connected to the slider and engageable with said locking member to lift the same to unlocked position during opening or closing movement of the slider, and means for normally urging said locking member to locked position when the pull member is released, and cooperating means on said locking member and pull for holding said locking member unlocked upon such release when the pull is in full forward position for opening the fastener.
3. A slider for slide fasteners of the class described, comprising a slider body, a locking member pivoted at one end to said slider body and having a locking projection on its other end, a pull tab attached to said locking member and having pivot lugs engageable with said locking member for lifting the same out of locking engagement during the opening or closing movements, and a notch in said locking member in position for retaining one of said pivot lugs during opening movement of the slider to hold said locking member in unlocked position even when the pull is released.
4. A slider for slide fasteners of the class described, comprising a slider body, a locking member pivoted at one end to said slider body for limited pivotal movement to locked and unlocked positions, said locking member having lengthwise extending recesses in its sides, a pull member having pivot lugs engaged in said recesses and adapted to transmit a lifting force to said locking member to lift it to unlocked position during opening or closing movements, and a spring operating on said locking member normally urging it to locked position, said recesses in the locking member having notches at their forward ends in which said pivot lugs will remain and hold the locking member out of locking engagement when the pull is released in opening the fastener.
5. A slider for slide fasteners of the class described, comprising a slider body, a locking member pivoted at one end of the slider body, a spring normally urging said locking member to locked position, said locking member being hollow and having recesses with inclined surfaces in its side walls, a pull member having pivot lugs projecting into said recesses and engageable with said inclined surfaces and a projection on the slider body adjacent the forward end of said recesses to retain the pivot lug of the pull member at the forward end of its travel, said pivot lugs having sufficient thickness to hold the locking member in unlocked position when the pull tab is released during opening movement of the slider.

RICHARD A. HATCH.
